United States Patent Office

Des. 196,778
Patented Nov. 5, 1963

196,778

CURTAIN WALL PANEL OR SIMILAR ARTICLE

Robert R. Keller, 41 Union St., Manchester, N.H.

Filed Nov. 1, 1962, Ser. No. 72,339

Term of patent 14 years

(Cl. D13—1)

FIG. 1.

FIG. 2.

FIG. 3.

FIG. 1 is a perspective view of a curtain wall panel showing my new design;

FIG. 2 is a vertical edge view thereof; and

FIG. 3 is a top plan view thereof.

The side opposite that shown in FIGURE 1 is substantially identical therewith.

I claim:

The ornamental design for a curtain wall panel or similar article, substantially as shown and described.
